UNITED STATES PATENT OFFICE.

CHARLES HOFF, OF CINCINNATI, OHIO.

BARREL-HOOP.

No. 840,212.

Specification of Letters Patent.

Patented Jan. 1, 1907.

Application filed October 28, 1905. Serial No. 284,859.

To all whom it may concern:

Be it known that I, CHARLES HOFF, a citizen of the United States of America, and a resident of Cincinnati, in the county of Hamilton and State of Ohio, have invented certain new and useful Improvements in Barrel-Hoops, of which the following is a specification.

This invention relates to improvements in devices for retaining hoops or bands on barrels, kegs, tubs, churns, and the like; and it consists in a flat metal hoop or band having intermediate its longitudinal edges a series of arrow-head or triangular shape stops or projections on its inner face, such stops comprising uncut indentations or impressions made in the outer face of the metal and retreating or becoming gradually deeper the thickness of the metal from the point to the base of the triangle and said point being directed toward the bilge edge of the hoop, whereby the hoop is provided with uncut sloping projections or spurs on its inner face to enter and anchor or embed themselves into the face of the barrel and resist accidental removal or slipping from place when once the hoop is properly driven on the barrel.

In the single sheet of drawings, forming a part of this specification, Figure 1 is a perspective view of a barrel-hoop embodying therein my invention; Fig. 2 an elevation of a barrel having its hoops provided with my improvement; Fig. 3, elevation of a fragmentary portion of my hoop, showing the inner face thereof; Fig. 4, an elevation showing a fragmentary portion of the outer face of my hoop; and Fig. 5, a vertical section taken on the dotted line $x-x$ of Fig 4, but showing a sectional portion of a wooden stave to bring more clearly to view the action of the hoop retainer or anchor in its embedding position in the face of the stave.

In the views, 1 represents an ordinary barrel-hoop, made of metal and of the size and shape to suit its position on the barrel, and 2 indicates each one of a series of retainer formations made in the hoop intermediate its circumferential edges and projecting from the inner face of the metal to make embedding contact with the face of the barrel and

to thereby resist accidental removal or slipping from place in holding the staves and the vessel together or intact. These retainer devices or formations are constructed thus: 55 An uncut indentation of substantially triangular or arrow-head shape is made or impressed, by means of a suitable tool, in the face of the hoop, thereby striking up or throwing the metal backward into a like- 60 shaped projection on the rear face of the hoop, none of the metal being cut away or cut through to weaken the hoop, but the same remaining intact. The body portion 3 of the retainer retreats or slopes backward 65 from the point or apex of the triangle to its base 4, and the latter is preferably curved or concaved in outline and beveled to provide a tapering walled cavity 5 on the back of the hoop, into which cavity the fibers of the 70 wooden stave A crowd or bury themselves, as seen in Fig. 5, when the hoop is driven "home" and the retainer embeds or anchors itself in the face of said stave. The body portion 3 has its point directed toward the 75 bilge edge of the hoop, (the arrow adjacent Fig. 5 indicating the direction of drive of the hoop,) and it slopes or bevels upward toward the concave base at its opposite end on the back of the hoop, so that when the 80 hoop is driven into place the said point substantially plows into the wood to guide and bury the projecting uncut beveled base, which forms an effectual stop to resist any accidental slipping of the hoop from place on 85 the barrel, but permits the forcible withdrawal of the hoop without material injury to the barrel.

I claim—

A sheet-metal barrel-hoop having on its 90 inner face one or more equilateral-triangle-shape stops each comprising an uncut retreating impression made in the face of the hoop intermediate its longitudinal edges, the apex or point of the triangle lying in the 95 direction of the bilge edge and the base of the same being concaved or curved and beveled toward said point, whereby, when the hoop is being driven into place the point of each stop plows into the face of the barrel 100 and guides the inclined stop or retainer projection into seating or embedding posi-

tion in the stave with the contiguous fibers of the stave crowded into the said concaved or curved and beveled base and resisting the accidental slipping of the hoop from place but permitting the forcible withdrawal of the hoop without material injury to the barrel, substantially as set forth.

Signed at Cincinnati, Ohio, this 21st day of October, 1905.

CHARLES HOFF.
